DESIGN FOR A COMB

Leo Seidner, Rockville Centre, N. Y., assignor to Bolta Comb Company, Inc., New York, N. Y., a corporation of New York

Application February 1, 1941, Serial No. 98,649

Term of patent 7 years

To all whom it may concern:

Be it known that I, Leo Seidner, a citizen of the United States, residing in Rockville Centre, county of Nassau, and State of New York, have invented a new, original, and ornamental Design for a Comb, of which the following is a specification, reference being had to the accompanying drawing, forming part thereof.

In the drawing:

Figure 1 is an elevation of one side of a comb showing my new design, the other side of said comb being identical with that illustrated, and Figure 2 is a top edge view of the comb.

The characteristic features of the design reside in the comb disclosed having medially disposed stepped portions thereon of the specific configuration shown.

I claim:

The ornamental design for a comb, as shown and described.

LEO SEIDNER.
